UNITED STATES PATENT OFFICE.

GEORGE WOBBE AND MAX WILLIAM WOBBE, OF SPRINGFIELD, OHIO.

DESIGN FOR A TRACE-HOLDER.

SPECIFICATION forming part of Design No. 32,828, dated June 12, 1900.

Application filed January 6, 1898. Serial No. 665,882. Term of patent 7 years.

To all whom it may concern:

Be it known that we, GEORGE WOBBE and MAX WILLIAM WOBBE, citizens of the United States, residing at Springfield, in the county 5 of Clark and State of Ohio, have invented and produced a new and original Design for Trace-Holders, of which the following is a specification, reference being had therein to the accompanying drawings, forming part 10 thereof.

Figure 1 is a plan view of a trace-holder for whiffletrrees, showing our design. Fig. 2 is an edge view of the same; Fig. 3, an end view thereof, and Fig. 4 a longitudinal sectional view through the longitudinal center 15 thereof.

The end C is curved, as clearly shown in Fig. 1, throughout the width of the tip G and is also rounded in the opposite direction, as 20 shown in Fig. 2. A rectangular hole F passes through the tip, as shown in Fig. 1. The raised surface E has one perpendicular face I' and is curved from the upper edge down to the surface of the holder proper, while the 25 bead-like projection F constitutes a bulge,

with curved outlines above the general surface of the holder.

In an end view, as shown in Fig. 3, the general outline of this holder, together with the projections E and F, is elliptical.

Viewed in plan, as in Fig. 1, the upper surface of the tip appears to be flat, with slightly-diverging edges, and as viewed in Fig. 2 the tip is thin along the edge C and also has diverging edges.

The leading or essential feature of our design comprises the shape of the trace-holder as an entirety, as shown.

Having thus fully described our invention, what we claim as new, and desire to secure by 40 Letters Patent, is—

The design for a trace-holder substantially as shown and described.

In testimony whereof we affix our signatures in presence of two witnesses.

GEORGE WOBBE.

MAX WILLIAM WOBBE.
